(57) **CLAIM**

The ornamental design for a automotive vacuum, as shown and described.

DESCRIPTION

FIG. 1 is a top, front and left-side perspective view of an automotive vacuum showing my new design;

FIG. 2 is a left end elevation view thereof;

FIG. 3 is a right end elevation view thereof;

FIG. 4 is a rear elevation view thereof;

FIG. 5 is a front elevation view thereof;

FIG. 6 is a top plan view thereof; and,

FIG. 7 is a bottom plan view thereof.

The details shown in broken lines form no part of the claimed design.
